UNITED STATES PATENT OFFICE.

JAMES CHARLES, OF RICHMOND, INDIANA.

SYSTEM OF HYDRAULIC-POWER UTILIZATION.

1,296,623.

Specification of Letters Patent. Patented Mar. 11, 1919.

Application filed November 16, 1918. Serial No. 262,792.

To all whom it may concern:

Be it known that I, JAMES CHARLES, a citizen of the United States, residing in the city of Richmond, in the county of Wayne, 5 State of Indiana, have invented a new and useful System of Hydraulic-Power Utilization, of which the following is a full, clear, and comprehensive specification and exposition, the same being such as will enable 10 others to construct and apply the same with exactitude.

The object of this invention, broadly speaking, is to provide a system of hydraulic power utilization which will be simple in character, practical in application, 15 comparatively easy to install, and in which the cost of maintenance will be practically nil.

More specifically stated my object is to 20 provide a system for conserving the water power, especially of small streams, whereby I am able to direct the water power to be delivered first through a first nozzle and then further directed and to be delivered 25 through a second nozzle, whereby I am able to utilize the full power directed ribbon like to a water-wheel or motor to be rotated thereby.

Other subsidiary and particular objects 30 will suggest themselves in the course of the following description, and that which is new will be correlated in the appended claims.

The preferred means for carrying out my invention in a practical and mechanically efficient manner is shown in the accompanying drawings, in which—Figure 1 is a top plan view of my complete construction. Fig. 2 is a vertical cross section as taken, for instance, on the line 2—2 of Fig. 1. And Fig. 40 3 is an end elevation of the second or delivery nozzle, the driven element being removed, and showing the head-gate or cutoff therebeyond.

Similar indices denote like parts throughout the several views.

In order that the theory and the principles of my invention may be more fully understood and appreciated I will now take up a detailed description thereof, in which 50 I will set forth the various features as fully and as comprehensively as I may.

Referring now to the drawings in concrete detail, letter A designates the basin, which is adapted to contain the head of accumulated water to be utilized, the said 55 basin being formed with walls B and B',

preferably of concrete, which rests on a base B''.

The inner faces of the walls taper from the apex or rim C downward and convergently to the vortex formed by the first nozzle or mouth D, which is formed segmental or curved horizontally as shown.

Connected with the nozzle D is the flume or conduit E, which projects at substantially 65 right-angles to the wall of the basin, and it rests on the base B''. The outer portion of the flume converges into the metal nozzle S, forming a continuation thereof, and said nozzle S has a slot or mouth F in the end 70 thereof, which is of less dimension than the nozzle D.

A head gate G, operative in the flume E, is adapted to provide means for cutting off the passage of water through the flume. 75

Letter H denotes the raceway by which water is admitted in the basin from the source of supply. And I denotes the overflow, to prevent the basin from overflowing.

Letter J denotes the water-wheel, the 80 same having the side flanges K—K', and with paddles or buckets L extending between the flanges and projecting from the periphery of the wheel. Said wheel is secured on the shaft M which is mounted for 85 rotation in the frame N. Also a pulley P is secured on the shaft M, from which the power developed may be taken to perform useful operations.

The lower peripheral portion of the wheel 90 revolves in the segmental race R which corresponds with the curvature of the wheel, thereby retaining the water in contact with the paddles of the wheel until the full force of the water is spent to rotate the wheel, 95 and the combined force of the concentrated pressure of the water results in revolving the wheel either at great speed or with a maximum of power.

In practice the gate G may be closed, after 100 which the basin A may be filled with water from the race H. Desiring now to transmit power to the pulley P one has only to raise the gate G a short distance, thereby permitting a ribbon of water to issue from 105 the mouth F of the nozzle S, which of course will be directed upon the paddles L of the wheel, thereby causing the wheel to revolve. It is evident that the comparatively large head of water in the basin A, concentrated 110 at D, and further concentrated at S, will issue from the slot F with tremendous force,

and all of this force will be exerted to revolve the wheel, thereby accomplishing the desideratum of this invention.

It is of course to be understood that a plurality of wheels may be mounted on the shaft M and that for each wheel a flume with nozzles may be extended from the basin, or the flume E may be provided with branch flumes each extending to its wheel, thereby further multiplying the power to be exerted on the shaft M. I desire that it be understood that the form and proportions of the several parts may be variously changed to meet varying conditions, without departing from the spirit of this invention or sacrificing any of the advantages thereof.

Having now fully shown and described my invention, what I claim and desire to secure by Letters Patent of the United States,

20 is—

1. A system of hydraulic power utilization including a permanent base, a basin formed thereon, the basin being formed with vertical outer walls and upwardly flaring inner walls terminating at their lower ends in a large slot-like nozzle, a flume connected with said nozzle and extending slightly downward from right-angle thereto, said flume being formed tapering both laterally and vertically, a small nozzle forming the terminal of the outer end of the flume the

same being located on the base and at a distance laterally from the basin, and a head-gate located in the flume, all substantially as shown and described and for the purposes set forth.

2. A system of hydraulic power utilization, including a base, a concrete basin formed on the base and integral therewith, the inner wall of the basin being formed convergent from its upper edge to the central lower portion thereof and terminating in a slot which opens into a flume extending outward upon the base at substantially right-angles to the basin, a raceway leading into the top of the basin, an overflow leading from the top of the basin, said flume being formed convergently from said slot, a metal nozzle forming the outer terminal of said flume and adapted to deliver a horizontal ribbon of water, and a head-gate adapted to control the flow of water through the flume, all substantially as shown and described, and for the purposes set forth.

In testimony whereof I have hereunto subscribed my name to this specification in the presence of two subscribing witnesses.

JAMES CHARLES.
